UNITED STATES PATENT OFFICE

152,375

DESIGN FOR A COMBINED CLEANING AND SCRAPING DEVICE

Sidney C. Seley, Erie, Pa.

Application January 31, 1947, Serial No. 136,552

Term of patent 14 years

(Cl. D9—6)

To all whom it may concern:

Be it known that I, Sidney C. Seley, a citizen of the U. S. A., residing at Erie, in the county of Erie and State of Pennsylvania, have invented a new, original, and ornamental Design for a Combined Cleaning and Scraping Device, of which the following is a specification, reference being had to the accompanying drawing, forming part thereof.

In the drawing:

Fig. 1 is a perspective view of a cleaning and scraping device, showing my new design;

Fig. 2 is a top plan view; and

Fig. 3 is a side elevational view thereof.

I claim:

The ornamental design for a combined cleaning and scraping device, as shown.

SIDNEY C. SELEY.
